A. B. Quinby,
Steam Safety Valve.
Patented Oct. 1, 1830.

1830-1831

The defendant offered to give the witness material and making part of the same containing and reflecting on the words of the last John Quincy himself of his informant on the mode of spreading effluvia in the soil
as of Almond Engines.

mercury, so that it is intended to allow of this being left off when the mercury is removed, so as to slide easily with the tube. The glass tube is intended to be surrounded with a suitable packing, and the manner of ordinary piston. From the top of it is to be extended a rod, with a
having a pointed or toothed rock a chisel on the container, which
shall give motion to an index and indicate the temperature of the
mercury and consequently that of the atmosphere.

When the piston or plunger rises to a certain height, resulting from the highest temperature which it is thought safe for the steam to attain, the head of it is to be made to press against a lever or other suitable contrivance whereby being raised, shall open or valve and let off the steam. The arrangement of this head is composed of an infinite number of vessels, one of which is exhibited in the drawing deposited in the Patent Office. This valve etc is let off steam in either a large or small quantity as may be required. And it is my desire and opinion to afford to escape only in such quantity as being conducted into a vessel formed like a bellows to give an alarm that the proper precautions will be immediately taken by the engineer.

As it is believed that an explosion never takes place until the temperature of the steam is greater than it ought to be, whether the quantity of water in the boiler be great or small, it is not thought necessary to accompany this invention with any other apparatus for showing the height of the water. The object in view is to obtain that information which shall be the means of guarding against an explosion. Whether the danger may arise from heating the water too highly or from what has been called bursting steam, which is produced when the water is of a temperature greater than it ought to be, referred to the vessel holding the water.

to give a voice to the people - to allow to open and sound and
discuss for the first time - as much as to produce larger, and
more salient, whether the same be done by the arrangement which it
has specified or by any other dependent upon the same principles.
